CLAIM

The ornamental design for a portion of a book with a drum implanted therein, as shown and described.

DESCRIPTION

FIG. 1 is a perspective view of a portion of a book with a drum implanted therein showing the invention, the book being shown in a closed position;

FIG. 2 is a left side view of the invention;

FIG. 3 is a top view of the invention;

FIG. 4 is a front view of the invention;

FIG. 5 is a right side view of the invention; and,

FIG. 6 is a second perspective view of the invention in an open position.

The broken lines defining the boundaries are shown for illustrative purposes only and form no part of the claimed design. The remaining portions of the book are shown in phantom line for environmental purposes only and form no part of the claimed design. The balls held loosely within and moveable within the enclosure of the drum are shown in broken lines as their exact position forms no part of the claimed design.
